CASING FOR BOILERS AND THE LIKE

Harold A. Brainard, Pittsburgh, Pa., assignor to
The General Fireproofing Company, Youngs-
town, Ohio, a corporation of Ohio

Application October 12, 1932. Serial No. 637,493

6 Claims. (Cl. 122—494)

This invention relates to sheet metal casings for boilers, radiators and the like, and has generally in view to provide an attractive sectional sheet metal casing the sections of which may be 5 economically produced and which are of such construction that they may be quickly and easily assembled in firm cooperative relationship entirely without the use of interconnecting fastening devices and without the use of special tools.

10 Sheet metal casings comprising front, rear and side sections have heretofore been constructed in which the front and rear sections are provided along their vertical edges with grooves or channels to receive the vertical edges of the 15 side sections. In assembling casings of this type it is usual to remove the front and rear boiler fittings, to apply the front and rear casing sections and to secure them in place against the boiler by reapplying the fittings against the outer 20 faces of the sections, and then to assemble the side sections by entering the bottom portions of their side edges in the top portions of the grooves or channels of the front and rear sections and to slide the side sections downwardly to their 25 final operative positions. This means, of course, that there must be a space above the tops of the front and rear sections at least equal in height to the height of the side sections in order to permit the latter sections to be initially engaged with the front and rear sections. Such 30 space frequently is not available and under such conditions difficulties are experienced in assembling the side sections with the front and rear sections, inasmuch as the only practical alternative is first to apply either the front or the 35 rear section, to then engage the side sections with the applied front or rear section, and then to apply the remaining front or rear section as the case may be by moving the same towards the 40 opposite section in order to cause the grooves or channels thereof to receive the related vertical edges of the side sections. While no particular difficulty may be experienced in engaging 45 the vertical edges of the side sections in the grooves of the first applied front or rear section, it is extremely difficult to engage the opposite vertical edges of the side sections in the grooves or channels of the last applied front or rear section 50 because of the narrow width of the grooves or channels and because access is denied to the interior of the casing by the last applied front or rear section, making it difficult to spring the side sections outwardly to aline their edges with 55 the grooves and requiring usually the services

of more than one workman to effect the assembly.

Sectional casings of other types also have been constructed heretofore, but these have been found to be disadvantageous primarily because 60 of the necessity of deforming one or another of the sections to effect their assembly with each other, or because of the necessity of employing separate fasteners to secure the sections together. 65

Accordingly, a special object of the present invention is to provide a casing comprising front, rear and side sections of such construction that they may readily and easily be assembled simply by relative lateral movement of the sections, and 70 without deformation of the sections or the use of bolts or other fastening devices between the sections, thus to avoid the disadvantages of prior casings of the type mentioned.

Another object of the invention is to provide 75 a top closure element composed of two sections constructed and connected together in a novel manner to facilitate their application over the top of the boiler or the like and upon the upper edges of the front, rear and side sections. 80

With the foregoing and other objects in view, which will become more fully apparent as the nature of the invention is better understood, the same consists in the novel features of construction, combination and arrangement of parts as 85 will be hereinafter more fully described, illustrated in the accompanying drawings and defined in the appended claims.

In the drawings, wherein like characters of 90 reference denote corresponding parts in the different views:—

Figure 1 is a top plan view of a sectional casing constructed in accordance with one practical embodiment of the invention and showing 95 the same operatively applied to a boiler, the top element of the casing being broken away to show the relationship between the side sections and the front and rear sections.

Figure 2 is a front elevation showing in full lines the sections of the top element in section and in their initial relative angular disposition during their assembly with the other sections, and, in dotted lines, showing the final operative position of said top element. 100

Figure 3 is an elevation of one of the side sections. 105

Figure 4 is an edge view of one of the side sections.

Figure 5 is a detail horizontal section show- 110

ing the manner of assembling the side sections with the front and rear sections; and

Figure 6 is an enlarged detail view showing the hinge connection between the sections of the top element.

Referring to the drawings in detail, it will be observed that the present casing comprises a front section A, a rear section B, side sections C, C and a top closure element D composed of 10 two half sections d, d.

At E in the drawings is designated a boiler of well known type composed of a plurality of connected water sections e the outer faces of which are inclined inwardly from medial points 15 as indicated at e'.

It is understood, of course, that the boiler E is inclusive of various appurtenances such as doors e² at the front thereof, a flue e³ at the rear thereof, and water pipes e⁴ at the top thereof, 20 and that in case of the doors e² or the like and the flue e⁴ or the like, such appurtenances are bolted or otherwise detachably secured to the boiler.

The front and the rear sections A and B of the present casing and, if necessary or desirable, also the side sections C, C thereof are formed with openings for alignment with the boiler appurtenances, and in this respect the front and the rear sections and the side sections 30 may differ from each other. In other respects, however, the front and the rear sections are duplicates of each other and the side sections are duplicates of each other, the front and the rear sections each having their side 35 marginal portions turned inwardly at substantially right angles to their body portions as indicated at 10, and the side sections being inwardly flanged along their side or vertical edges, preferably throughout their lengths, as indicated 40 at 11.

For purposes of strengthening and imparting rigidity to the inturned marginal portions 10 of the front and rear sections A and B said in-turned marginal portions at their free edges 45 preferably are turned inwardly upon themselves as indicated at 12. Regarding the inturned flanges 11 of the side sections C, C, it will be observed that said flanges are disposed at included obtuse angles with respect to the planes 50 of the side sections and, at points suitably spaced along their lengths, are provided with inwardly projecting tongues 13, constituted by integral inward continuations of the flanges disposed in the planes of the respective flanges as shown. 55 Moreover, each tongue at its inner or free edge has an inwardly directed flange 14 disposed at the same, or substantially the same, inclination relative to the plane of the related side section C as the inclined outer faces e' of the boiler 60 sections have relative to the plane of the side of the boiler.

In assembling the present front, rear and side casing sections about a boiler the boiler appurtenances at the front and the rear thereof are detached and either the front or the rear casing section A or B first is disposed in operative relationship to the boiler and is secured thereto by reapplying the related appurtenances. For example, the rear section B first is secured 75 in place by bolting the flue casting e³ against the outer face thereof. Next, the side sections are placed in position as illustrated in Fig. 5 with the tongues 13 at one side thereof entered between the terminal boiler section e and the in-turned side marginal portions 10 of the applied

front or rear section, as the case may be, in which connection it is pointed out that the front and the rear sections are of such width that the marginal portions 10 thereof are disposed, in the applied positions of said sections to the boiler, outwardly from the sides of the boiler an amount substantially equal to the amount that the tongues 13 project inwardly from the side sections C. With the side sections placed as stated, pressure is exerted to force the tongues 13 into the spaces between the terminal boiler section e and the inturned side portions 10 of the applied and secured front or rear plate and at the same time sharp blows are delivered 80 against the side plates in the vicinity of the entered tongues 13 to cause the same to fully enter the mentioned spaces with their flanges free ends 14 engaged flat against the inclined faces of the terminal boiler section and with the adjacent side marginal portions of the side sections engaged beneath the inturned marginal portions of the applied front or rear section. Finally, the remaining front or rear section, as the case 85 may be, is secured in position against the boiler by reapplying the related boiler appurtenances, and the tongues 13 at the adjacent sides of the side section are engaged between the adjacent terminal boiler section and the inturned marginal portions 10 of the last applied front or 90 rear section, the reapplied appurtenances then being tightened to hold the sections in assembled relationship.

In assembling the sections in the manner indicated the obtuse angular relationship of the tongues 13 relative to the planes of the side sections is slightly reduced due to the overall width of the side sections being slightly greater than the front to rear dimension of the boiler. Consequently, the constant tendency of the side sections is to move outwardly under the influence 110 of the energy stored in the tongues 13 by reason of their inward deflection, with the result that the side sections are maintained tightly engaged along their side edges against the inturned side marginal portions 10 of the front and the rear 115 sections. In this connection it is apparent, of course, that while the wedging action between the inclined faces of the boiler sections e and the free edges of the tongues 13 assists in moving the side sections outwardly when the obtuse angular relationship of the tongues to the side sections is reduced by the inward pressure of the front and the rear sections against said tongues, 120 this wedging action is not essential and the side sections will be forced outwardly if the sides of the boiler sections are flat.

Referring now to the top closure element D, it will be observed that the inner marginal portion 16 of one of the half sections d thereof is stepped downwardly relative to the body portion thereof and that said section is provided at the junction of said marginal and body portions thereof with openings 17. It will also be observed that the other section d is provided along its inner marginal edge with projecting tongues 18 which align 130 with the openings 17 when the sections are in mating relationship, and that said tongues also are stepped downwardly and turned upon themselves as indicated at 19. Thus it is apparent that by disposing the sections in downwardly 135 and inwardly inclined relationship as illustrated by full lines in Fig. 2, the tongues 18 may be engaged in the openings 17 to connect the sections, and that when the sections subsequently are swung downwardly to a common horizontal 140

plane they are securely held against relative separation.

The inner edges of the sections *d*, *d* are provided with mating recesses 20 to accommodate 5 appurtenances extending upwardly from the boiler and, as is understood, these recesses are alined with the appurtenances at the same time the tongues 18 are entered in the openings 17, whereby the appurtenances extend upwardly 10 through the top closure when the sections thereof are swung downwardly to their operative positions in which they rest on the upper edges of the front, rear and side sections.

Preferably the top closure sections *d*, *d* are 15 marginally flanged downwardly as indicated at 21 to impart an attractive finish to the top of the casing, and in this connection, both to impart strength and rigidity to the top closure and to provide flanges to engage the upper edges of 20 the front, rear and side sections, the marginal down-turned flanges 21 preferably are turned inwardly and upwardly upon themselves, as indicated at 22, and then are flanged laterally inwardly, as indicated at 23, the said flanges 23 25 being provided for engagement with the upper edges of the front, rear and side sections as is understood.

Without further description it is thought that the features and advantages of the invention 30 will be readily apparent to those skilled in the art, and it will of course be understood that changes in the form, proportion and minor details of construction may be resorted to, without departing from the spirit of the invention and 35 scope of the appended claims.

I claim:—

1. A sectional casing for boilers and the like comprising front and rear sections having inwardly directed side marginal portions, and side 40 sections for disposition between the boiler or the like and the said inwardly directed marginal portions of the front and rear sections, said side sections having inwardly directed side marginal portions disposed at included obtuse angles to 45 the body portions of the side sections to seat against the boiler or the like and to be moved relatively inward by the front and the rear sections thus to force the side sections outwardly 50 against the inturned side marginal portions of the front and the rear sections.

2. A sectional casing for boilers and the like comprising front and rear sections having inwardly directed side marginal portions, and side sections for disposition between the sides of the 55 boiler and the said inwardly directed side marginal portions of the front and rear sections, said side sections having inwardly directed stiffening and reinforcing flanges along their side edges and further having tongues constituting 60 inwardly directed continuations of said flanges, said tongues being disposed at included obtuse angles to the body portions of the side sections to seat at their free or inner ends against the boiler and to be engaged and forced relatively 65 inwardly by the front and the rear sections thus

to force the side sections outwardly against the inturned marginal portions of the front and the rear sections.

3. A sectional casing for boilers and the like comprising front and rear sections having inwardly directed side marginal portions, side sections for disposition between the front and the rear sections with their side marginal portions underlying the inwardly directed side marginal portions of the front and the rear sections, and inwardly directed formations on the side marginal portions of the side sections to be engaged by the front and the rear sections and to be forced relatively inwardly by relative inward movement of the front and the rear sections and operable by such movement to force the side sections outwardly against the inwardly directed side marginal portions of the front and the rear sections.

4. A sectional casing for boilers and the like comprising front and rear sections having inwardly directed side marginal portions, side sections to be disposed between the front and the rear sections with their side marginal portions underlying the inwardly directed side marginal portions of the front and the rear sections, and elements projecting inwardly from the side sections to seat against the boiler or the like and disposed to be moved relative thereto by the front and the rear sections to force the side sections outwardly against the inwardly directed side marginal portions of the front and the rear sections.

5. In combination with a boiler or the like, a sectional casing therefor comprising side sections disposed at the sides of the boiler, front and rear sections disposed at the front and the rear of the boiler and secured to the boiler by appurtenances thereof, said front and rear sections having inwardly directed side marginal portions overlying the side marginal portions of the side sections, and inwardly directed formations on the side sections disposed at included obtuse angles to the body portions of the side sections and seated against the boiler sides and urged inwardly by the front and the rear sections whereby the side sections are urged outwardly against the inwardly directed side marginal portions of the front and the rear sections.

6. A sectional casing for boilers and the like comprising front, rear and side sections and a top closure element, the top closure element comprising two separate sections one stepped downwardly at its inner edge and having openings at the junction of its body and stepped marginal portion, and the other having downwardly stepped tongues projecting from its inner edge for engagement in said openings, whereby the sections are connectible and disconnectible when they are disposed in other than a common plane and whereby they are held against relative separation when they are disposed in a common plane.

HAROLD A. BRAINARD. 140
